UNITED STATES PATENT OFFICE.

GEORGE C. PYLE, OF CUYAHOGA FALLS, OHIO, ASSIGNOR TO THE AMERICAN ELECTRIC HEADLIGHT COMPANY, OF INDIANAPOLIS, INDIANA.

ELECTRIC LAMP.

SPECIFICATION forming part of Letters Patent No. 331,327, dated December 1, 1885.

Application filed September 27, 1884. Serial No. 144,136. (No model.)

To all whom it may concern:

Be it known that I, GEORGE C. PYLE, of Cuyahoga Falls, in the county of Summit and State of Ohio, have invented certain new and useful Improvements in Electric Lamps; and I do hereby declare the following to be a full, clear, and exact description of the same, reference being had to the accompanying drawings, forming a part of this specification, and to the figures and letters of reference marked thereon.

My present invention relates more especially to that class of electric-arc lamps known as "focusing-lamps," and designed for use as substitutes for the ordinary oil-lamps, in connection with the reflectors of locomotive head-lights; and my said invention consists, generally, in the provision made for properly focusing the arc within the reflector and in the manner of effecting the positive, uniform, and proportional feeding of the carbons, whereby a constant and steady arc is maintained, which is unaffected by any jarring or thumping motions which may be communicated to the mechanism.

The application, in a practical and commercial sense, of an electric-arc lamp to locomotive head-lights as ordinarily constructed, and as a substitute for the oil-lamps, is a problem of no inconsiderable magnitude. It is essential that the light should be uniform and steady, and to secure this desideratum it is necessary to so construct and arrange the operating mechanism of the lamp that its feed shall not be injuriously affected or controlled by the sudden jars and shocks to which the lamp is unavoidably subjected when in operation. It is, moreover, of the utmost importance that the lamp should be so mounted and arranged relative to the reflector that it will be at all times accessible for inspection and repair, and so that its carbons can be readily and expeditiously adjusted within the reflector and the arc located in the proper focal position.

It has been found in practice that the electric-arc lamps as ordinarily constructed, especially those employing a gravity or gravitating feed, are impractical for use on a locomotive, or in any other place or situation where they are subjected to violent shocks. The reason is obvious. In order to maintain

the requisite degree of stability in the arc, it is necessary that the mechanism governing and controlling the feed of the carbons should be extremely delicate and sensitive, and to this end, in the majority of cases, the operating of the feeding mechanism is made dependent more or less upon the action of gravity. As is well known, any pendulous or pivoted weight, even though balanced more or less by springs, &c., acquires, when subjected to violent jar or concussion, a force or movement by reason of its inertia, and the motion so produced, being in proportion to the weight and rapidity of the movement, cannot be accurately compensated for, and must, therefore, of necessity become a disturbing element, interfering materially with the action of the feeding mechanism, which is set to a fixed normal standard.

Numerous efforts have no doubt been made and improvements suggested with a view to overcoming the defects pointed out and others inherent in such lamps, but, so far as I am informed, without arriving at the required degree of uniformity and certainty under all conditions.

In the accompanying drawings, illustrating an embodiment of my said invention, Figure 1 is a side elevation of my improved lamp; Figs. 2 and 3, rear and side (opposite to that shown in Fig. 1) elevations, respectively, of the mechanism for controlling the feed; Fig. 4, a top plan view of the supporting and adjusting frame; Fig. 5, a view enlarged, showing the gear-train for operating the carbon-carriers. Figs. 6 and 7 illustrate modifications of the mechanism for causing the separation of the carbons. Fig. 8 is a diagrammatic view of the circuits.

Similar letters of reference in the several figures indicate like parts.

The plate A, constituting the base proper of the lamp, is provided with vertical guides or ways a a , at or near one end, to receive the removable yoke a' , and with horizontal ways b b , to receive the vertical post or frame B, a screw, b , fastened to said post, passing through the yoke a' and held by the nuts b' b' , serving to adjust the post longitudinally of the plate A. The working mechanism of the lamp is mounted upon and entirely supported by the frame or standard C, which lat-

ter is arranged to slide vertically in ways formed upon or in the post B, the vertical adjustment being effected through the medium of a screw, c, passing through a step or bearing, c', and engaging a bearing, b, attached to the post B. This much of the frame-work is very similar to that described in my application No. 132,203, filed May 20, 1884, and is not herein claimed.

As set forth in my said prior application, the base A may advantageously be applied directly to the sliding board of the head-light, but when so arranged and intended to replace the oil-lamp heretofore generally employed it is found desirable that provision be made, in addition to the vertical and longitudinal adjustments described, for positioning the carbons longitudinally of the reflector, so as to locate the arc at the proper focal point. The longitudinal adjustment may be effected in many obvious ways—such, for example, as by pivoting the base-plate A, as at a³, to the sliding board and providing an arc-shaped slot, as at a⁴, through which is passed a screw or bolt. As thus arranged, the frame and attached carbons can be swung in the arc of a circle upon the pivot a³ toward or from the center of the reflector, and the length of the radius can be increased or diminished by changing the position of the post B upon the base A. I do not, however, wish to be limited to the specific device shown, as many different arrangements will be at once suggested to those skilled in the art for carrying into effect this feature of my invention, which comprehends the longitudinal adjustment of the carbon-carrying mechanism with respect to the reflector. The frame or standard C, which, as before stated, carries all the working mechanism of the lamp, is arranged to set diagonally upon or with relation to the base-plate A, in order the better to accommodate and adapt the lamp to the ordinary head-light, this feature being common to my prior application and is claimed therein.

The standard C is provided with two ways or guides, C' C², adapted to support two sliding bars or racks, D D', the one, D, carrying the holder for the upper carbon, and the other, D', the holder for the lower carbon. The bars D D' are provided with teeth d, with which engage the pinions E E', fixed to a shaft, E², supported in an oscillating bearing, e, the latter being supported on a pivot, e', secured to the standard C, intermediate the bars D D'. The pinion E is approximately twice the diameter of the pinion E', to compensate for the unequal consumption of the positive and negative electrodes; hence the upper or positive carbon is given a movement twice as great as the lower or negative carbon to each revolution of the shaft E². A very slight, if any, preponderance of weight is given to the upper-carbon carrier or its support D, and in any event only sufficient to cause the approach of the carbon-carriers when free, due allowance being made for the

difference in the size of the pinions E E'. A spring, e², may, if found desirable, be applied to the oscillating bearing e, to supplement the weight of the upper-carbon carrier and insure the dropping of the inner end of the shaft E² when the lamp is not in operation, and to still further guard against the accidental sticking of the bars D D', and to provide for the proper separation of the carbons when the inner end of the shaft E² is elevated, as hereinafter described. The pivot e' of the bearing e is located nearest the pinion E'. At some convenient point on the frame are placed pins e⁴, (whose position may be adjusted, if desired,) between which the shaft E² is permitted to vibrate, and which serve to limit and adjust the range of movement. These devices, to which the carbons are attached, and through which the requisite motions to feed the carbons and form the arc are transmitted, constitute what is herein referred to as a "carbon-actuating mechanism," it being that part of the lamp mechanism which, being connected to and actuated by a suitable driving or feed-controlling mechanism, communicates the movement to the carbons.

Various forms and descriptions of feeding mechanism can be readily employed and applied in connection with the devices thus far described for effecting the necessary movements to feed the carbons and form the arc, the requisites of such a feeding mechanism being, first, a means for elevating the inner end of the pivoted shaft, thereby separating the carbons and forming the arc without the necessity of moving back or reversing the motion of the shaft, and, second, a mechanism operating to rotate the shaft and feed the carbons together in proportion as they are consumed, thus regulating and maintaining the proper arc.

I have devised several feeding mechanisms independent of and each adapted for use in connection with devices such as described for effecting the movements of the carbons, and in the accompanying drawings I have illustrated one form, which, as has been demonstrated by practical tests, is adapted not only to so feed the carbons as to produce a steady light, but to accomplish this operation when subjected to violent shocks and jars, such as are produced by a locomotive running at a high speed.

The mechanism referred to consists, essentially, of an electro-magnet which, when the circuit is closed through the carbons, operates to raise and to sustain in its elevated position the inner end of the operating-shaft E², a feeding mechanism applied to the said operating-shaft and set in motion by a second electro-magnet located in a branch circuit, said mechanism operating to rotate the shaft, and thus cause the simultaneous approach of the carbons to maintain the arc, and a third electro-magnet located in a shunt-circuit and operating, when the resistance of the arc is abnormally increased, to close the said branch circuit, and

thereby set in action the feeding mechanism. On the inner end of the oscillating shaft E^2 is secured a pinion, F , through which motion is transmitted to said shaft from the feeding mechanism; or frictional gearing may be employed, if desired. The feeding mechanism proper is supported in a frame, G , located beneath the electro-magnet G' , and provided at the top with an armature, G^2 , facing the pole-pieces of said magnet. The frame G is permitted a limited vertical motion, and to this end it is supported and guided at the top upon pins g, g of non-magnetic material secured to pole-pieces of the electro-magnet G' or other convenient portion of the frame, and at the bottom on a pin, g' , in a bearing, g^2 , attached to the frame C . Mounted in suitable bearings in this movable frame G are two shafts or spindles, $G^3 G^4$. The upper shaft, G^3 , is arranged beneath, but in the same vertical plane as the shaft E^2 , and carries a small pinion, g^3 , for engagement with the pinion F , and a large pinion, g^4 , gearing into the small pinion g^3 on the shaft G^4 . On the shaft G^4 is mounted a suitable clutch or equivalent device for giving motion to the gear-train at the proper intervals, said mechanism consisting in this instance of the flanged disk or wheel G^5 , secured to the shaft G^4 , an arm or link, g^6 , pivoted upon said shaft, a link, g^7 , carrying a grooved or slotted block embracing the flange of the wheel G^5 , a link, g^8 , pivoted to the arm g^6 at one end, and at the other to the inner end of the link g^7 , and a spring, g^9 , bearing against the arm g^6 and link g^7 , and causing the latter, when raised, to firmly grasp the rim or flange of the wheel G^5 , and thus turn the latter, at the same time permitting the said link g^7 to move freely in the opposite direction. In order to prevent the backward movement of the wheel G^5 as the clutch moves down to take a fresh hold, it is advisable to employ a brake acting upon said wheel G^5 , and as a convenient means for applying such a device I have mounted upon the end of shaft G^3 a spring, g^{10} , the two arms of which make contact with and press upon the periphery of the wheel G^5 . It is obvious, however, that other forms of brake mechanism and differently applied may be used with like effect. This feeding mechanism constructed and applied as described possesses several novel and valuable features which are entirely independent of the particular devices for actuating the clutch so long as the movement necessary to maintain the arc is secured.

So long as there is no current passing through the coils of the electro-magnet G' , and until the circuit is established and a current of sufficient strength to sustain the feeding mechanism passes through the coils, the frame G remains down, the pinion g^3 drops below and out of contact with the pinion F , the operating-shaft E^2 falls and rests against the lower stop, and the carbon-carriers, being thus left free to move by gravity, the carbons are gradually brought together until their proximate ends

are brought into contact. The circuit now being established, the current passes through the coils of the electro-magnet G' , attracting the armature G^2 , thus raising the frame G and holding it elevated so long as the current is maintained above the minimum strength necessary to raise the said frame G . As the frame G rises the pinion g^3 is brought into contact with the pinion F on the operating-shaft E^2 , thereby causing the teeth on said pinions to mesh and at the same time elevating the inner end of the shaft E^2 , thus separating the two carbons to form the arc. During this vertical movement of the frame G , which at once effects the application of the feeding devices to the operating-shaft and the separation of the carbons to form the arc, no backward movement of the operating-shaft or feeding mechanism is effected, nor can any take place, owing to the presence of the clutch and brake and the arrangement of the gearing.

The mechanism above described as borne by the frame G constitutes what is herein referred to as the "feed mechanism," being that part or portion of the lamp mechanism which operates upon and gives motion to the carbon-actuating mechanism before referred to, and it is in turn operated upon and the requisite movements produced by feed-controlling mechanism, which latter will now be described.

The arc having been formed and the feeding mechanism brought into position to operate it, it only remains to attach an efficient mechanism to operate, at the proper intervals, upon the clutch to effect the gradual approach of the carbons as they are consumed, and thereby maintain the arc. The mechanism provided in this instance for actuating the arm g^6 of the clutch consists, essentially, of an electro-magnet, H , preferably located in a branch of the main circuit, and an electro-magnet, I , preferably of relatively higher resistance located in a shunt circuit around the lamp, the last-named electro-magnet operating, when the resistance of the arc is abnormally increased, to close the branch circuit, in which the electro-magnet H is included, causing the latter to actuate the feeding mechanism until the resistance of the arc is sufficiently diminished by the approach of the carbons.

The armature H' of the electro-magnet H is carried by an arm or lever, H^2 , pivoted to the frame G , as at h . This lever H^2 carries an arm, h' , pivoted to the arm g^6 of the clutch, and at its lower end it is provided with a plate or block, h^2 , preferably of some insulating material, to the sides or faces of which latter are secured the contact springs or plates h^3 . These springs or plates h^3 work between and upon the switch plates or contacts $h^4 h^5$, there being preferably two sets of said plates and springs—one set on either side of block h^2 —the better to maintain electrical contact and facilitate the action of the said springs h^3 . The contacts $h^4 h^5$ are secured to a plate or block of insulating material, h^6 , or otherwise suitably insulated from their support. The

armature I' of the electro-magnet I is attached to a lever, I², pivoted at i upon the block h⁶, and carrying an adjustable contact, i', which, acting in conjunction with a contact, i², closes 5 the circuit through the feed-operating electro-magnet H. The armature I' is retained in position in front of the electro-magnet I by means of an adjustable link or bolt, i³, attached to lever I², bearing against a projection or yoke, i⁴, and the resistance to the attraction of the said electro-magnet I is determined and regulated by means of an adjusting-screw, i⁵, bearing against a spring, i⁶; but other suitable mechanism well known as 10 applicable for the purpose may be employed. A spring, h⁷, is likewise applied to draw the lever H² away from the electro-magnet H.

The circuit-connections for the several electro-magnets and switches are arranged as follows: From the binding-post J extends a wire, j, to the switch-plates h⁴, and from the latter extends a wire, j', to the electro-magnet G'. The coils of the electro-magnet G' and H, preferably of about the same resistance, are connected by a wire, j², and from the last-mentioned electro-magnet H extends a wire, j³, terminating at the insulated plate K, carrying the contact i². The lever I², carrying the contact i', is connected by a wire, j⁴, with switch-plates h⁵. The lower-carbon carrier is connected 15 to the binding-post J' by a wire, j⁵, and the upper-carbon carrier to the wire j², intermediate the electro-magnets G' H, by a wire, j⁶. The electro-magnet I, being in a shunt-circuit, 20 may conveniently be connected by wires j⁷ to the binding-post J² and switch-plates h⁴, respectively.

As thus constructed, arranged, and connected, the current entering the binding-post J 25 will pass to the switch-plates h⁴, and a portion of it will at all times pass through the coils of the electro-magnet I to the opposite binding-post, J'. The main portion of the current will, however, owing to the difference in the resistance of the two circuits, pass from the switch-plate h⁴ through the coils of the electro-magnet G', thence to the upper and lower carbons, and 30 by wire j⁵ to binding-post J'. The electro-magnet G' being thus energized, raises its armature, and with it the feeding mechanism supported in frame G, thus causing the carbons to separate, forming the arc. So long as the 35 arc is formed, be it longer or shorter than the normal, the frame G will remain elevated, but if from the breaking of the carbons or opening 40 of the main circuit the current passing between the carbons should cease, the frame G will instantly drop, thus allowing the carbons to feed together in readiness for action. As 45 the carbons are consumed and the resistance of the arc increases, a larger proportion of the current finds its way through the shunt-circuit, energizing the electro-magnet I sufficiently to 50 overcome the force of the reacting-spring i⁶, and bring the points i' i² in contact, thus closing 55 at this point the circuit through electro-magnet H. The current which previously

passed from binding-post J to plate h⁴, and thence through electro-magnet G' to the upper carbon, is now caused to divide, part passing 75 through the circuit just traced, and part from switch-plates h⁴, through contact springs or plates h³ on lever H², to switch-plate h⁵, and thence to lever I', points i' i², electro-magnet H, to upper carbon. Immediately the electro-magnet H becomes energized it attracts its armature and operates the clutch mechanism to effect a slight feed of the carbons; but as the lever H², to which the armature H' and clutch-arm are connected, is moved toward the electro-magnet H the contact-springs h³, carried by 80 said lever, are withdrawn from the switch-plates h⁴, thus breaking the circuit through the electro-magnet H, thereby releasing the lever H² and permitting the spring h⁷ to draw 85 it back, when the connection is again made and the armature attracted.

It will thus be seen that so long as the electro-magnet I is sufficiently energized to hold the points i' i² in contact, and this occurs only 90 when the resistance of the arc is abnormally increased, the lever H² will be caused to vibrate rapidly, thereby effecting a determinate feed of the carbons, and as soon as the resistance of the arc is reduced to the normal the 95 circuit will be broken at i' i² and the feeding mechanism remain *in statu quo*, ready at all times to be again operated.

It will also be noticed that at no period is there a break in the circuit between the binding-posts J J', the circuit through the electro-magnet G' being at all times closed so long as the lamp is operating.

In practice it is usual to employ electro-magnets G' and H of about the same resistance; 105 but this is not found to be essential, although, when any material variation exists between the two, it is advisable that the electro-magnet G' should offer less resistance than the electro-magnet H. The reciprocations given to the lever H² are so rapid that in practice it has been found profitable to so proportion the gearing that the carbons shall at each reciprocation of the clutch be moved about the .035 of an inch, thereby increasing the power 110 exerted by the clutch and in the same proportion more readily preventing any accidental movement of the carbons, at the same time securing a regular, positive, and almost continuous feeding of the carbons proportional 115 to the increased resistance in the arc due to the burning away of the points.

Although I have shown and described what is termed the "feeding mechanism" as mounted wholly upon the moving frame, I do not 125 wish to be understood as limiting my invention to such construction, inasmuch as this part of my invention pertains, broadly, to the application of an independent feeding mechanism to the operating-shaft of the carbon-carriers, whereby the latter are, when the lamp is not in operation, disconnected from the feed; hence to accomplish this, though 130 with not so good an effect, the operating-shaft

might be elevated and sustained by the electro-magnet G', and thus be brought into contact with the feed mechanism mounted in a stationary frame, as shown in Fig. 6. Moreover, the same result can be accomplished by mounting the feed mechanism in a fixed frame and supporting that portion through which the motion of the feed mechanism is communicated to the carbon-operating shaft, upon a movable frame connected to the armature of the electro-magnet, as shown in Fig. 7.

I claim as my invention—

1. In combination, with the reflector and the base upon which it is mounted, a plate attached to said base and carrying the working mechanism of an electric-arc lamp whose carbons are located within the reflector, said plate being pivotally attached to the base and provided with a clamping-screw, as described, whereby the plate can be secured at different points about the pivot and the carbons adjusted within the reflector, substantially as described.

2. In combination with the reflector and the vertically and laterally adjustable frames carrying the operating mechanism of an electric-arc lamp, the base-plate upon which said adjustable frames are supported, pivoted at one side of the reflector and held in adjusted position by a clamp, substantially as described, whereby the carbons can be swung in the arc of a circle longitudinally of the reflector.

3. The combination, in an arc lamp, of two reciprocating carbon-carriers, an intermediate shaft connected to and operating upon said carriers to cause their simultaneous approach and recession, an oscillating support for said shaft, and an electro-magnet operating through suitable connections to tilt the operating-shaft, and thus cause a separation of the carbons, substantially as described.

4. The combination, in an arc lamp, of two reciprocating carbon-carriers, an intermediate oscillating operating-shaft connected thereto, a movable feeding mechanism, and an electro-magnet for bringing said feeding mechanism into operative connection with said shaft, substantially as described.

5. In an arc lamp and in combination with the reciprocating carbon-carriers and the oscillating connecting and operating shaft, a separate feeding mechanism mounted in a movable support and actuated by an electro-magnet to bring said feeding mechanism into connection with the operating-shaft and oscillate the latter, whereby the arc is formed and the feeding mechanism placed in operative connection with the carbon-carriers, substantially as described.

6. The combination, in an arc lamp, and with an oscillating shaft controlling the movements of the carbon-carriers, of an independent feeding mechanism adapted to engage said operating-shaft, and an electro-magnet located in the main line and adapted, when the current is established, to bring the feeding mechanism

into operative connection with the oscillating shaft and sustain the same in position, substantially as described.

7. In an arc lamp, and in combination with an oscillating operating-shaft connected to and controlling the movements of the carbon-carriers thereof, an independent feed mechanism for actuating said operating-shaft and an electro-magnet for bringing said feed mechanism into connection with the operating-shaft when the current is established, substantially as described.

8. In an arc lamp, and in combination with the carbon-carriers and operating-shaft thereof, an independent feeding mechanism normally disconnected from said operating-shaft, and an electro-magnet for bringing the feeding mechanism into operative connection, substantially as described.

9. In an arc lamp containing two movable carbon-carriers, and an intermediate shaft supported in an oscillating bearing and so connected to the carriers as to control their movements, and in combination with said shaft, an independent feed mechanism carrying a driver for engaging and rotating the said shaft, and an electro-magnet in the main circuit acting, when energized, to bring the said driver into engagement with the said oscillating shaft, substantially as and for the purpose set forth.

10. In an electric-arc lamp, and in combination with an independent feed mechanism and the two carbon carriers, the intermediate shaft connected to the said carriers and mounted in a pivoted bearing, substantially as described, whereby when the lamp is not in operation the carbons are caused to approach by the action of gravity and independent of the feeding mechanism, substantially as described.

11. In an arc lamp, and in combination with the movable carbon-carriers and their operating-shaft supported in an oscillating bearing, an independent feed mechanism rotating in one direction only, and an electro-magnet operating to connect said feed mechanism and operating-shaft when the current is established through the carbons, substantially as described.

12. In an electric lamp containing two reciprocating carbon-carriers, and a connecting operating-shaft sustained in pivoted bearings and in combination with said shaft and the gear attached thereto, an independent feed mechanism provided with a pinion for engagement with the gear on the oscillating shaft, and an electro-magnet operating to raise said pinion into engagement with said gear, vibrate the said operating-shaft and hold the latter in position so long as the current is maintained, substantially as described.

13. In an arc lamp, and in combination with the mechanism connected with the carbon-carriers to actuate them, an independent feed mechanism, and mechanism for automatically

connecting the feed mechanism and carbon-actuating mechanism when the lamp is in operation, substantially as described.

14. In an electric lamp wherein the feed mechanism is independent of the carbon-actuating mechanism and connected thereto automatically when the lamp is in operation, and in combination with said feed mechanism, a feed - controlling mechanism the actuating-magnet whereof is located in a branch of the main circuit, substantially as described.

15. In combination with the carbon-actuating mechanism, the independent feed mechanism, and the electro-magnet controlling the movement of the feed mechanism toward and from the carbon-actuating mechanism, a feed-controlling mechanism consisting, essentially, of an electro-magnet in a branch circuit, mechanism controlled thereby for alternately opening and closing said circuit to actuate the clutch, and an electro-magnet in a shunt-circuit for closing said branch circuit, substantially as described.

16. As a means for actuating the feeding mechanism of an arc lamp, and in combination with the clutch applied thereto, an electro-magnet in a branch circuit, a lever controlled by said electro-magnet and connected to said clutch, a circuit-breaker operating in unison with said lever and located in said branch circuit, and an electro-magnet in a shunt-circuit for closing said branch circuit, substantially as described.

17. In an arc lamp, and in combination with the carbon-actuating mechanism and the pivoted shaft thereof, the independent feeding mechanism mounted in the reciprocating frame, the electro-magnet actuating said frame and thereby applying the feed mechanism to the carbon-actuating mechanism, and a feed-controlling mechanism for operating the feed mechanism, substantially as described.

18. In an arc lamp wherein are included a carbon-actuating mechanism, an independent feeding mechanism, and a feed - controlling mechanism, an electro-magnet in the main circuit applied to the feeding-mechanism to sustain the latter in operative connection with the carbon - actuating mechanism, a second electro-magnet located in a branch of the main circuit, a third electro - magnet located in a shunt-circuit and operating to close the branch circuit, and a switch mechanism located in the branch circuit and operating to alternately

open and close said circuit and thereby actuate the brake mechanism, substantially as described.

19. In an electric lamp, and in combination with the carbon-feeding and arc forming mechanism thereof, the electro-magnet located in the branch circuit, the electro-magnet in the shunt-circuit, the circuit-breaker actuated by the magnet in the shunt-circuit, the armature connected to the switch and clutch, and the switch-plates connected, respectively, to the branch and main circuits, substantially as described.

20. In an electric lamp, and in combination with the carbon-carriers and pivoted operating-shaft, the feeding-train mounted in the vertically-reciprocating frame and carrying the pinion for engagement with a pinion on the operating-shaft, the electro-magnet operating upon said frame to connect the feed mechanism and raise the operating-shaft, and a clutch actuated by suitable controlling mechanism applied to said feed mechanism, substantially as described.

21. In combination with the flanged driving-wheel G^5 , applied to the feed mechanism, the grooved block g^7 , pivoted to the arm g^8 , attached to the lever g^6 , and the spring g^9 , carried by said lever and pressing upon the pivoted block g^7 to hold it in engagement with the flange of the driving-wheel G^5 , substantially as described.

22. In an electric lamp, and in combination with the carbon-carriers and operating-shaft thereof, an independent feed mechanism rotating intermittently and in one direction only, and an electro-magnet controlling the application of said feed mechanism to the operating-shaft of the carbon-carriers, substantially as described.

23. In combination with the feeding devices, and as a means for actuating the same, an electro-magnet in a branch of the main circuit for driving the feed mechanism, a circuit-breaker included in said circuit and actuated by the before-mentioned electro-magnet, and an electro-magnet in a shunt-circuit controlling a switch in the said branch circuit, substantially as described.
